UNITED STATES PATENT OFFICE

127,291

DESIGN FOR A FLOWER CONTAINER

Richard Gottlieb Block, Los Angeles, Calif.

Application August 13, 1940, Serial No. 94,398

Term of patent 3½ years

To all whom it may concern:

Be it known that I, Richard Gottlieb Block, a citizen of the United States of America, residing in the city and county of Los Angeles and the State of California, have invented a new, original, and ornamental Design for a Flower Container, of which the following is a specification, reference being had to the accompanying drawing, forming a part thereof. Figure 1 is a side elevational view of a flower container showing my new design. Figure 2 is a front perspective view thereof; and Figure 3 is a side view opposite to that shown in Figure 1.

I claim:

The ornamental design for a flower container, as shown.
